UNITED STATES PATENT OFFICE.

CHARLES HULTGREN, OF CHICAGO, ILLINOIS, ASSIGNOR TO S. KARPEN & BROS., OF CHICAGO, ILLINOIS, A CORPORATION OF WEST VIRGINIA.

SOFA BED.

Application filed February 14, 1921. Serial No. 444,724.

The present invention relates particularly to sofa beds of the type in which the cushions of the sofa are adapted to be spread on the bed sections in the extended condition of the structure to serve as a mattress for the bed.

The primary object is to provide an improved and simplified construction having an improved mode of operation.

10 The invention is illustrated in its preferred embodiment in the accompanying drawings, in which—

Fig. 1 represents a vertical sectional view of the structure in extended condition, the 15 section being taken as indicated at line 1—1 of Fig. 2; Fig. 1^a a broken section on an enlarged scale taken approximately as indicated at line 1^a of Fig. 1; Fig. 2 a plan sectional view taken as indicated at line 20 2—2 of Fig. 1; Fig. 3 a sectional view corresponding with the section shown in Fig. 1, but showing the structure in the folded or sofa form; Fig. 4 a sectional view taken as indicated at line 4—4 of Fig. 1; and Fig. 25 5 a broken vertical section taken as indicated at line 5 of Fig. 1.

In the embodiment shown, A represents a main frame provided with a back A', end standards or arms A² and front and rear 30 cross members A³ and A⁴ extending longitudinally of the main frame and connecting the base portions of the end standards; a front bed section B, which in the folded condition of the structure is superposed 35 over the rear section and becomes the seat portion on which the cushions are supported; a rear bed section C which is adapted to be lowered in the frame when the structure is converted to sofa form; 40 a front mattress section B' and a rear mattress section C' supported by the bed sections B and C, respectively, the mattress section C' being adapted to fold forwardly upon the section B' about the point or line 45 1, preparatory to converting the structure to sofa form; and a pair of parallel levers fulcrumed on each end of the main frame and carrying the bed sections, each pair comprising a front lever D and a rear lever D'.

50 The frame A may be of any suitable construction and design. It is shown as comprising substantial end standards or arms which are rigidly connected at their back portions by the back A', the lower portions

of the end standards being staunchly connected together by the rails or stringers A³ and A⁴. The main frame is preferably equipped with casters 2.

The frames of the bed sections B and C are alike in construction, but the bed section B is preferably slightly longer than the bed section C, as will be understood from Fig. 2. Each bed section frame comprises a marginal angle iron 3 and metal cross strips 3^a which, at their points of intersection, support the coil springs 3^b.

The end members of the frame 3 of the front bed section have riveted to their rear portions metal attaching plates or strips 4; and the end members of the rear bed sections have riveted to their front portions metal attaching strips 5. Firmly secured to the inner surface of each end standard at the lower front portion thereof is a metal mounting-plate 6.

The levers are of elbow form, the elbow portions of the front levers being pivotally connected with the front portions of the mounting plates 6 by pivots 7, and the elbow portions of the rear levers being connected with the rear portions of the mounting plates 6 by pivots 8. Each lever has a forwardly-extending long arm 9 which inclines upwardly somewhat as shown in Fig. 1, and has an upstanding short arm 10. 85 The long arms of the front levers are connected with the front portions of the plates 4 of the front bed section by pivots 11; and the long arms of the rear levers are connected with the rear portions of said plates 4 by pivots 12. The short arms of the front levers are connected with the front portions of the plates 5 of the rear bed section by pivots 13; and the short arms of the rear levers are connected with the rear portions of the plates 5 by pivots 14. In the operation of converting the structure to sofa-form, the pivots 11 and 12 follow the large arcs shown by dotted lines in Fig. 1 and move to the points designated 11^a and 12^a; and in this movement, the pivots 13 and 14 move to the points designated 13^a and 14^a. The positions of the pivots 11 and 12 in Fig. 3 correspond with the positions of the points 11^a and 12^a in Fig. 1; and the position of the pivots 13 and 14 in Fig. 3 correspond with the position of the points 13^a and 14^a in Fig. 1. As appears from

Figs. 1^a and 4, the short arms of the levers are offset away from the end standards so as to bring them into proper planes for connection with the plates 5 and the rear bed section; and the offset condition of the short arms of the front levers affords spaces between the upper ends of said short arms and the inner surfaces of the end standard of the main frame for accommodating the long arms of the rear levers when the structure is in the extended position.

The front edge of the front bed section is equipped with legs 15 which are adapted to rest upon the floor in both the extended 15 and the folded condition of the structure. The folding operation is limited by the legs striking the floor when the structure is converted to sofa-form, at which time the front bed section is in position to rest upon the rear bed section and also to be supported by the long arms of the levers. If desired, the end standards of the main frame may be equipped near their lower rear corners with stops or supports 16 upon which the 20 rear portion of the lower bed section may rest in the folded condition of the structure.

The front edge of the front bed section is also equipped with a suitably upholstered 30 front piece 17 which forms a front piece for the main frame when the structure is in sofa-form, at which time the ends of the front piece are housed by the front portions of the end standards of the main frame. Preferably the front piece extends 35 somewhat above the plane of the upper ends of the coil springs 3^b, so that the front edge of the mattress or cushion will bear against the projection.

40 The mattress sections, it will be understood, are supplied with a covering suitable for cushions; or, in any event, the surfaces which are exposed when the structure is in sofa-form are so covered.

45 From the description given, it will be understood that when the structure is to be converted from the bed form shown in Fig. 1 to the sofa-form shown in Fig. 3, the mattress section C' is folded forwardly onto the mattress section B'; the front section is then lifted and shoved rearwardly and is carried by the long arms of the levers to a position superposed about the rear section, the rear section settling down in 50 the main frame as the operation proceeds and the front section being finally housed between the arms of the main frame. The reverse operation will be understood without further description. The conversion 55 from one form to another may be effected readily with the exertion of comparatively slight force.

60 It will be understood that the bed sections are carried by parallel movements, owing to the parallel relation of the corre-

sponding arms of the levers. The rear edge of the rear bed section is, in the extended condition of the structure, a sufficient distance in front of the back A' of the main frame to permit the slight rearward movement which is necessary in the operation of dropping the rear bed section from the position shown in Fig. 1 to the position shown in Fig. 3. At the end of this movement, the rear bed section is centered in the main 70 frame, from front to rear, in a position corresponding with its position when it is elevated.

75 It is desirable that one set of levers, at least, should be tied together, the purpose 80 being to insure simultaneous movement of the levers at both ends of the sofa-bed, and avoid racking and binding. This is preferably accomplished by extending a tie-rod 12^b between the front ends of the rear 85 levers. The end-portions of this tie-rod (Fig. 5) are journaled in the members 4, thus furnishing the pivots 12; and the extremities of the tie-rod are made angular and riveted through angular perforations in 90 the front ends of the long arms of the pair of levers D'. In this manner all of the levers are caused to turn together, even though the lifting on the front bed section be done at one side of the longitudinal center.

95 It is preferred to provide the bed sections with counterbalancing means which will aid in converting the structure from bed form to sofa form, and vice versa. This 100 preferably is accomplished by means of a spring 18 which has its rear end secured to the back-portion of the sofa frame and has its front-portion secured to the rear bed section some distance back of its center. This spring is under tension when the structure is in the extended position and also when it is in the folded position. It 105 will be noted that the spring swings about its rear end connection in the operation of 110 converting the structure.

115 The construction is exceedingly simple, capable of being cheaply manufactured, and may be made staunch and durable without difficulty.

120 The foregoing detailed description has been given for clearness of understanding only, and no unnecessary limitations should be understood therefrom, but the appended claims should be construed as broadly as permissible in view of the prior art.

What I regard as new and desire to secure by Letters Patent, is:

125 1. In a structure of the character set forth, the combination of a main frame front and rear bed sections, the front section being somewhat longer than the rear section, and a pair of parallel levers fulcrumed on each end of the main frame and having short arms carrying the rear bed section 130

and having long arms carrying the front bed section, said short arms being offset from the plane of the long arms and the long arms of the rear set of levers swing-
5 ing to a position below the bed-section pivots carried by the extremities of the short arms of the front set of levers, in the operation of converting the structure to bed form.

2. In a structure of the character set forth, the combination of a main frame, front and rear bed sections, a pair of angular levers at each end of the structure and having their elbow portions fulcrumed on an end of said frame, said levers having short 10 arms pivotally connected with the rear bed-section and long arms pivotally connected with the front bed-section, a longitudinal connecting rod having its end portions rigidly connected with the long arms of one 15 set of levers, said rod affording the pivotal connections between said last-mentioned arms and front bed-section, the long arms of the rear set of levers being adapted to work past the upper ends of the short arms 20 of the front set of levers when the structure is in the extended position and the short arms of said levers being adapted to carry 25 the rear bed-section rearwardly a substantial distance and then forwardly substantially the same distance in the operation of

folding the structure, and coil springs having their front ends connected with the rear bed-section and having their rear ends connected with stationary supports disposed at a plane intermediate between the upper and 35 lower positions of the rear bed-section.

3. In a structure of the character set forth, the combination of a main frame, a pair of angular levers at each end of said frame, said levers having their elbow portions fulcrumed on the frame and having upstanding short arms and forwardly-extending long arms, the long arms of the rear levers being adapted to swing past the extremities of the short arms of the front 40 levers in the operation of converting the structure to the bed-form, front and rear bed sections mounted respectively on the short arms and the long arms of said levers, and a mattress on said bed sections, said 45 mattress having a rear section adapted to be folded forwardly onto the front section to afford a cushion, said levers being adapted to carry the front section rearwardly and lower it substantially to the level it occupies 50 in the open position and to lower correspondingly the rear bed-section, the rear section in the operation of converting the structure from bed form to sofa form. 55

CHARLES HULTGREN.
